UNITED STATES PATENT OFFICE.

STEPHEN A. DOBYNE, OF ST. LOUIS, MISSOURI, ASSIGNOR TO CHAMPION SHOE MACHINERY COMPANY, OF ST. LOUIS, MISSOURI, A CORPORATION OF MISSOURI.

SOLE-SEWING MACHINE.

1,201,160.

Specification of Letters Patent. Patented Oct. 10, 1916.

Application filed March 12, 1913. Serial No. 753,751.

To all whom it may concern:

Be it known that I, STEPHEN A. DOBYNE, a citizen of the United States, and residing at St. Louis, in the State of Missouri, have 5 invented certain new and useful Improvements in Sole-Sewing Machines, of which the following is a specification.

This invention relates to sewing machines and more particularly to sole sewing machines of the type shown and described in Patent No. 473,870.

One of the objects of this invention is to construct a machine in which the parts are so arranged that the work may be readily removed from the machine at the completion of sewing a shoe, and to provide means whereby the machine may be readily stopped in that position.

Another object is to construct novel thread 20 controlling mechanism, and provide novel thread measuring means, by means of which each stitch will be set accurately and uniformly.

Further objects will appear from the detail description taken in connection with the accompanying drawings, in which:

Figure 1 is a front elevation of a sole sewing machine embodying this invention, Fig. 2 is a plan view, the cams and shaft being shown dotted, Fig. 3 is a side elevation from the left side of the machine, Fig. 4 is a side elevation from the right side of the machine, Fig. 5 is a detail side elevation of the thread measuring mechanism, Fig. 6 is a detail section on the line 6-6 Fig. 5, Fig. 7 is a section on the line 7-7 Fig. 5, Fig. 8 is a detail side elevation of the thread lock or clamp, Fig. 9 is a section on the line 9-9 Fig. 8, Fig. 10 is a detail side elevation of the 40 needle guide operating means, Fig. 11 is a front elevation, and Fig. 12 is a section on the line 12-12 Fig. 9, parts being shown in elevation.

Referring to the accompanying drawings 45 15 designates a column upon which is mounted a head or base 16 having brackets 17 and 18 for supporting a driving shaft 19. A series of cam wheels 20, 21, 22 and 23 are keyed to the driving shaft and are provided with 50 cam grooves for operating the various parts of the machine. The cam wheel 20 has a cam groove which operates the feed slide 24, and another cam groove which operates the thread lifter 25. The cam wheel 21 is provided with cam grooves for operating the

presser foot 26, the looper 27 and the awl 28. The cam wheel 22 is provided with cam grooves for operating the needle 29, the looper 27, the shuttle 30 and the thread finger 31. The cam wheel 23 is provided with 60 cam grooves for operating the thread clamp, the needle guide and the thread measurer. The construction, except as hereinafter described, is substantially the same as in said patent, and as in application Serial No. 631,290, filed June 5, 1911.

The presser-foot 26 co-operates with a work support 35 of usual construction and is provided with a handle 36 whereby it may be raised and lowered by hand, and with a latch 37 engaging a keeper 38. The presser-foot operating cam groove in the cam wheel 21 has two cam portions, one of which unlocks the presser-foot during the feeding of the work and the other of which (a short cam portion) unlocks the presser-foot when the awl and needle are out of the work and when the thread lock or clamp is open. The arm 39 on the presser-foot has pivotally mounted thereon an arm or link 40 provided 75 with a block 41 which is adapted to be engaged by a beveled lug 42 on the cam roll 21 to raise the presser-foot while the thread-lock is open and while the awl and needle are out of the work. The construction and operation of this presser-foot mechanism is 85 fully shown and described in application Serial No. 735,213, filed December 6, 1912.

The cam wheel 20 has a cam groove engaged by a cam roll 46 on one arm 47 of a lever pivoted at 48 on the bracket 17. The other arm 49 of this lever is connected by a link 50 to an arm 51 on one end of a shaft 52 mounted for rotative movement in a bore in the head 16 and in a bracket 53 on the head. A take-up lever 54 is mounted on the other end of the shaft. A thread tension comprises a pair of thread engaging disks 55 mounted on a shaft supported on the machine head and held in clamping engagement 100 by a spring 56 on the shaft, the tension of this spring being adjusted by nuts 57. An auxiliary take-up 58 of usual construction is mounted on the machine head.

A shaft 60 extends through the machine head and this shaft has loosely mounted thereon a hollow shaft or sleeve 61 having a bearing in a bracket 62 on the machine head. An arm 63 is mounted or formed on the shaft 61 and carries a roll 64 for the 105 110

thread. The other end of the sleeve has clamped thereon an arm 65 which has pivoted thereon a block 66 on which is movable a slide 67. This slide is pivoted at 68 to a 5 lever 69, pivoted at one end on the bracket 18 and pivotally connected at its other end with a link 70. This link 70 is pivotally connected with an arm 71 rigidly connected to one end of the shaft 60. The other end of the 10 shaft 60 which extends through the machine head has an arm 72 connected by a link 73 with the arm 39 on the presser-foot. The pivotal connection between the link 70 and the arm 71 is formed by a pin 74 in the link 15 70 having an eccentric 75 extending through the link 71. The pin 74 is provided with a slotted head so that it may be adjusted and this pin is locked in adjusted position by a clamping screw 76 adapted to contract the 20 split end of the link 70, and by a lock nut 77 on the pins 74. A lever 78 is pivoted intermediate its ends on the bracket 18 and one end of this lever has a cam roll 79 engaging a cam 80 in the cam wheel 23, while the other 25 end of the lever 78 is connected by a link 81 with the upper end of the slide 67.

The cam groove 80 will oscillate the lever 78, and this lever will in turn move and oscillate the slide 67 on its pivot 68. The 30 oscillation of the slide 67 will in turn oscillate the arm 65 which will in turn move the thread arm 63 up and down. If the lever 69 be lowered the action of the slide 67 on the arm 65 will be increased so that the 35 stroke of the lever 63 will be increased. On the other hand if the slide 67 be raised by raising the lever 69 the stroke of the lever 63 will be decreased. The interconnection of the lever 69 with the presser-foot is such 40 that as the presser-foot is raised for thicker material the lever 69 is lowered so as to increase the stroke of the thread arm 63, and as the presser-foot approaches the work support the stroke of the thread arm will decrease. The stroke of the thread arm therefore varies automatically with the thickness of the work. The stroke of the thread arm 45 63 may be independently and manually adjusted by means of the adjustable eccentric connection between the link 70 and the 50 arm 71.

The sleeve 61 has mounted thereon between the bearing 62 and the arm 63 a sleeve 55 which has an arm 86 adapted to coöperate with a grooved sheave 87 on the machine head. Another arm 88 on the lever has a cam roll 89 working in the cam groove 90 on the cam wheel 23. The cam roll 89 is mounted upon the eccentric part 91 of a pin 60 92 mounted in the arm 88 and having a knurled head 93 whereby it may be adjusted. The end of the lever is split so that it may be contracted by a clamping screw 94 to hold the pin 92 in adjusted position. By means 65 of this construction the cam roll 89 may be

adjusted with respect to the lever 88 to accurately adjust the engagement between the arm 86 and the sheave 87.

The path of the thread is shown in Fig. 3. The thread passes from a wax pot (not 70 shown) between the sheaves 55, over the sheave 64 on the thread measuring arm 63, under the sheave 87 of the thread clamp, over the auxiliary take-up 58, and over the take-up 54 to the stitch forming mechanism. 75 The timed relation of the stitch forming mechanism and of the thread controlling mechanism is the same as in the patent heretofore referred to. The thread measuring arm moves down to measure the thread while the thread is clamped between the sheave 87 and the arm 86 and while the take-up moves down to take up and set the stitch. The thread so measured is thereafter given up to the auxiliary take-up. The thread 80 measuring arm will automatically measure the thread in accordance with the thickness of the work through the connection of the thread measurer operating means with the presser-foot as heretofore described, and this 85 connection can be independently adjusted by means of the eccentric connection between the presser-foot and the thread measurer operating means.

A bell crank lever 95 is mounted on a 95 shaft journaled in the bracket 18 and this lever has one arm provided with a cam roll 96 coöoperating with the cam groove 97 in the cam roll 23. The other arm of the bell crank lever has a tooth 98 meshing with 100 teeth 99 on a lever 100 pivoted intermediate its ends on the machine head, and having at its other end teeth 101 meshing with a segment 102 on the needle guide. The teeth 98 and 99 are shaped to form the teeth of a 105 bevel gear. By means of this construction the needle guide is operated positively in both directions.

The timed relation of the mechanisms in this machine is substantially the same as 110 that in the machine of the patent. A cycle of operations is as follows: The presser-foot being locked to clamp the stock, the awl rises to pierce the work, the presser-foot is released, the awl feeds the work, the awl is 115 retracted, the needle pierces the work, the presser-foot is locked, the needle is retracted, the take-up rises to give up the thread, the shuttle takes the loop, the thread clamp opens, the thread measurer moves down to 120 give up the thread to the auxiliary tension, (the thread clamp being open at this time, while the presser-foot is also unlocked for a short period), the take-up moves down to 125 clamp the thread, and the thread measurer rises to measure or draw the thread from the supply.

In order to remove the work from the machine the procedure is as follows: The op- 130

erator backs up the machine to cause the lug 42 to engage the block 41 and raise the presser-foot. The engagement between the lug and block takes place while the short portion of the presser-foot cam unlocks the presser-foot and while the awl, needle and thread clamp cams are in position so that when the presser-foot is raised the awl and needle will be out of the work while the thread clamp will be open to release the thread. The work can therefore be removed at this point. It will be noted that the raising of the presser-foot and the positioning of the other parts is performed upon a mere reversal of the machine. The presser-foot raising mechanism furnishes a convenient means for placing the parts in proper position and for determining when the parts are in proper position to permit removal of the work.

It is obvious that various changes may be made in the details of construction without departing from the spirit of this invention, and it is therefore to be understood that this invention is not to be limited to the specific construction shown and described.

Having thus described the invention what is claimed is:

1. In a sewing machine, thread controlling mechanism comprising a support, an oscillating shaft mounted in said support, a thread measuring arm secured to said shaft to oscillate therewith, a thread clamping arm loosely mounted on said shaft to oscillate thereon, and means for operating said shaft and said thread clamping arm, said measuring and clamping arms being arranged on one side of said support.

2. In a sewing machine, thread controlling mechanism comprising a support, a shaft mounted to oscillate in said support, a thread clamping arm mounted to oscillate on said shaft, a thread measuring arm secured to one end of said shaft to oscillate therewith, an operating arm secured to the other end of said shaft, and means for operating said thread clamping arm and said operating arm, said measuring and clamping arms being arranged on one side of said support.

3. In a sewing machine, thread controlling mechanism comprising a shaft, a sleeve mounted on said shaft, a thread measuring arm mounted on said sleeve to move therewith, a thread clamping arm mounted to oscillate on said sleeve, and means for operating said thread clamping arm and said sleeve.

4. In a sewing machine, thread controlling mechanism comprising a shaft, a sleeve mounted on said shaft, a thread measuring arm mounted on said sleeve to move therewith, a thread clamping arm mounted to oscillate on said sleeve, means for operating said thread clamping arm and said sleeve,

and adjusting means for said thread measuring arm.

5. In a sewing machine, thread controlling mechanism comprising a shaft, a sleeve mounted on said shaft, a thread measuring arm mounted on one end of said sleeve, an operating arm mounted on the other end of said sleeve, a thread clamping arm mounted to oscillate on said sleeve, an actuating connection to said operating arm, and means connected to said shaft for adjusting said actuating connection.

6. In a sewing machine, thread controlling mechanism comprising a thread measuring arm, an operating arm connected thereto, a slide having a sliding connection with said operating arm, a lever for pivotally supporting said slide to oscillate on said lever, means for oscillating said slide on said lever, and means concentric with one of said arms for adjusting said lever.

7. In a sewing machine, thread controlling mechanism comprising a shaft, a thread measuring arm mounted to oscillate on said shaft, adjustable means for operating said arm, a presser-foot connected to oscillate said shaft, and an adjusting connection from said shaft to said operating means.

8. In a sewing machine, thread controlling mechanism comprising a shaft, a thread measuring arm mounted to oscillate on said shaft, an operating arm connected with said thread measuring arm, an adjustable actuator for said operating arm, and an adjusting connection between said shaft and said actuator.

9. In a sewing machine, thread controlling mechanism comprising a shaft, a thread measuring arm mounted to oscillate on said shaft, an operating arm connected with said thread measuring arm, an actuator having a sliding connection with said operating arm, and means on said shaft for sliding said actuator.

10. In a sewing machine, thread controlling mechanism comprising a shaft, a thread measuring arm mounted to oscillate on said shaft, an operating arm connected with said thread measuring arm, an actuator slide engaging said operating arm, and an arm on said shaft connected to adjust said actuator slide.

11. In a sewing machine, thread controlling mechanism comprising a shaft, a thread measuring arm mounted to oscillate on said shaft, an operating arm connected with said thread measuring arm, an actuator slide engaging said operating arm, a movable support for said slide, means for oscillating said slide, and an arm on said shaft connected to said movable support.

12. In a sewing machine, thread controlling mechanism comprising a shaft, a thread measuring arm mounted to oscillate

on said shaft, an operating arm connected with said thread measuring arm, an actuator slide engaging said operating arm, a lever for pivotally supporting said slide, means for oscillating said slide, an arm on said shaft connected to said lever, and a presser-foot connected with said shaft.

13. In a sewing machine, thread controlling mechanism comprising a shaft, a thread measuring arm mounted to oscillate on said shaft, an operating arm connected with said thread measuring arm, an adjustable actuator for said operating arm, an arm on said shaft, an adjustable connection between said actuator and said arm and a presser foot connected with said shaft.

14. In a sewing machine, thread controlling mechanism comprising an oscillating shaft, a thread measuring arm secured to said shaft to oscillate therewith, a thread clamping arm loosely mounted on said shaft to oscillate thereon, a controlling shaft within said first shaft, and an operating connection to said thread measuring arm controlled from said controlling shaft.

15. In a sewing machine, thread controlling mechanism comprising an oscillating shaft, a thread measuring arm secured to said shaft to oscillate therewith, a thread

clamping arm loosely mounted on said shaft 36 to oscillate thereon, means for operating said thread measuring and clamping arms, a controlling shaft within said first shaft, and a presser-foot connected to operate said controlling shaft.

16. In a sewing machine, thread controlling mechanism comprising an oscillating shaft, a thread measuring arm secured to said shaft to oscillate therewith, a thread clamping arm loosely mounted on said shaft 40 to oscillate thereon, means for operating said thread measuring and clamping arms, a controlling shaft within said first shaft, a presser-foot connected to operate said controlling shaft, and means operated on said controlling shaft for controlling said measuring arm.

17. In a sewing machine, thread controlling mechanism comprising a thread clamp, a cam, an arm connected to said thread clamp, a cam roll, and a pin for said cam roll having an eccentric bearing in said arm.

In testimony whereof I affix my signature in the presence of two witnesses.

STEPHEN A. DOBYNE.
